DEVICE OR APPARATUS FOR TREATING
HAIRAlbert Shelby and Carl F. Hilgeman, Buffalo,
N. Y.; said Hilgeman assignor to said Shelby

Application July 11, 1941, Serial No. 401,928

26 Claims. (Cl. 132—36)

This invention relates to a device or apparatus for treating live or growing human hair, and particularly for straightening curly, frizzly or kinky hair; and has for a primary object to provide a practical, desirable and efficient device or apparatus of novel construction for such purpose.

The device comprises a casing having a movable cover or section adapted to be opened to permit tresses, locks or portions of the hair of a subject's head to be enclosed and properly arranged in a treating chamber formed by the casing, and means for subjecting the hair in the casing to the softening or modifying action of steam or a hot vapor to effect a desired treatment of the hair. While subjected to the action of the steam or vapor, the hair may be straightened by subjecting it to tension or a stretching action, preferably by means of a succession of pairs of rolls between which the hair passes and is gripped and which are rotated for stretching the hair. The casing is preferably mounted on a stand or support equipped with adjusting means whereby the casing can be adjusted to and held stationary in any relation to the subject's head that may be necessary to most conveniently and efficiently treat successive or different tresses, strands or portions of the hair on various portions of the head.

One object is to provide a device with efficient heating means or elements for heating moisture or liquid in the casing to generate steam or hot vapor directly therein and provide control means whereby the necessary heat and moisture in the treating chamber can be quickly produced and regulated, as may be required, for a particular treatment of the hair.

Other objects of the invention are to equip the casing with heating means, preferably comprising a plurality of electrical heating elements, for heating water or other suitable liquid held in absorbent material in the casing for generating steam or vapor, and control means for energizing one or more of the elements, as may be necessary, and for shutting off the current to the element or elements at the end of a predetermined period of time; also to provide absorbent material or bodies in the treating chamber adapted to absorb surplus liquid or condensate and prevent the same from escaping from the casing with possible annoyance, discomfort or injury to the subject.

Further objects and advantages of the invention will appear from the following specification of the preferred embodiment of the invention, shown in the accompanying drawings, and the novel features of the invention are set forth in the appended claims.

In said drawings:

Fig. 1 is a plan view of a hair treating ap-

paratus embodying the invention, showing the two hinged sections of the casing in open position.

Fig. 2 is a fragmentary side elevation of a portion of the casing showing the two sections in partially closed relation.

Fig. 3 is a fragmentary plan view of one of the hinges connecting the casing sections showing the parts in closed position.

Fig. 4 is a diagram illustrating the electrical connections between the heating elements, the control switches and the source of current.

Fig. 5 is a side elevation of the apparatus, mounted upon the upper end of an adjusting stand or support.

Fig. 6 is a partial front elevation thereof.

Fig. 7 is a fragmentary, sectional plan view of the apparatus on line 7—7, Fig. 11.

Fig. 8 is a fragmentary rear elevation of the apparatus.

Figs. 9 and 10 are fragmentary, enlarged sections of the hinge connection between the casing sections, respectively showing the parts in partially closed position and in fully closed position, the sections being taken respectively on line 9—9 of Fig. 2 and on line 10—10, Fig. 3.

Fig. 11 is a transverse sectional elevation of the casing in closed, operative position.

Fig. 12 is a fragmentary, longitudinal section on line 12—12, Fig. 11.

Fig. 13 is a fragmentary, longitudinal section on line 13—13, Fig. 11, illustrating the driving connection for roll-operating worm shafts.

Fig. 14 is a longitudinal section on line 14—14, Fig. 15, of one of the electric heating elements for generating steam in the treating chamber.

Fig. 15 is an end elevation thereof.

Fig. 16 is a fragmentary, horizontal section showing the means for mounting the support for the heating elements in the casing.

15 represents the casing which forms the hair treating chamber 16. This casing preferably is of rigid walled construction, of generally rectangular shape in plan and relatively shallow, and comprises a lower section or body and a cover or section 17 which is movably connected to the body to adapt it to be opened for placing and arranging the tress of hair in the treating chamber and to be closed so as to enclose the hair in the treating chamber. At one end, the casing 15 is preferably reduced in depth or tapered, as by making the body with an upwardly and outwardly inclined end wall 18, and the body and cover are formed with protruding portions or lips 19 between which the hair enters the treating chamber, thereby adapting the casing to be adjusted, as may be necessary, to place the lips 19 close to the scalp in position to grasp between them a desired tress of hair close to its roots. The joint between the casing sections may be sealed, as by means of a suitable packing gasket

20 seated in a groove in the rim of the body and against which the rim of the cover engages when the casing is closed.

Clamping means are preferably provided at the lips 19 of the casing, of a construction capable of gripping the tress of hair close to the scalp and holding it firmly so as to prevent discomfort to the subject incident to the stretching of the hair when straightening it. For this purpose, clamping strips 21 of suitable resilient material, such as rubber, are shown, secured to and extending between the lips 19, so that when a tress of hair is placed in the open casing and the cover closed, these clamping strips will tightly grip and hold the root ends of the hair. The clamping strips are of sufficient thickness and resilience to conform to the irregularities in thickness of the tress of hair so as to firmly hold it and also tightly close the joint between the casing sections at this end. Narrow strips 22 of wood or other suitable heat-insulating material are also preferably secured to the lips outside of the clamping strips for preventing objectionable conduction of heat to the subject's head in the event of contact of the strips with the head.

Preferably the cover is hinged to the casing body by hinge means which enable the cover section to swing toward and from and also move lengthwise relatively to the body section. As shown, for this purpose, the cover is provided at one side with hinge lugs 23 which are adapted to turn and slide on hinge pins 24 each secured at its ends in spaced lugs 25 fixed to the adjacent side of the body. The fixed lugs 25 are spaced far enough apart to allow the cover lugs to slide on the hinge pins sufficiently to permit a substantial movement of the cover lengthwise relatively to the body. Thus, when opening the cover, it can be first lifted slightly, then moved lengthwise away from the subject's head and then swung fully open, thereby preventing it from striking the head. This is desirable, for instance, when treating hair at the back of the neck below the protruding base portion of the head, and by preference, the cover is positively prevented from being fully opened until it has been first shoved backwardly away from the head. For this purpose, the cover may be provided with a rigid projection 26 on one of the hinge lugs 23 which, when the cover is closed, overlies a rib or part 27 rigid with and extending lengthwise of the casing from one hinge lug 25. When the cover is in closed position, the projection 26 is spaced upwardly somewhat away from the rib 27 so as to permit a limited upward swing of the cover sufficient to allow the hand to be inserted into the casing to smooth or arrange the tress of hair therein, but the cover cannot be swung to its full open position until it has first been moved rearwardly far enough for the projection 26 to clear the rear end of the rib 27. In closing the cover it can be first swung to a partially closed position, then moved lengthwise close to the head and then closed against the casing body.

Any suitable means may be provided for drawing the cover tightly down against the body and fastening it in its closed position. Lever fastenings 28 of known type are shown for the purpose. A handle 29 is shown at the free edge of the cover as a convenient means for manipulating or opening and closing the cover.

Steam or hot vapor is preferably generated in the treating chamber for conditioning the hair

for straightening it, or for other treatments, by heating water or other suitable conditioning liquid in the casing by means of one or more electrical heating elements. Three such heating elements 30 are shown in the casing 15, see Fig. 7. Each of these elements as illustrated (see Figs. 14 and 15), comprises a body 31 of suitable absorbent material, for example, asbestos cloth, retained between opposite side plates 32 of Bakelite or other suitable insulating material, which are secured together so as to clamp the absorbent material between them, by hollow rivets 33, 34, passing through and riveted in holes in the ends of the side plates 32. An electrode 35, preferably consisting of a strip of wire screening or thin perforated metal, is secured at one end to the rivet 34, and extends therefrom between layers or folds of the absorbent material. Opposite electrodes 36, consisting of thin strips of suitable metal, are secured to and extend from the other rivet 33 at opposite sides of the first electrode 35, being preferably disposed between folds or layers of the absorbent material and being held thereby from contact with the middle electrode 35. The middle electrode 35 may be secured between spacing sleeves 37 clamped on the rivet 34 between the side plates 32, and the two electrodes 36 may be clamped between the side plates 32 and a spacing sleeve 38 surrounding the rivet 33 between the electrode strips. The two electrodes 36, of one polarity, are in electrical connection with the rivet 33, and the electrode 35, of opposite polarity, is in electrical connection with the other rivet 34, so that when the rivets 33, 34 are placed in electrical connection with the opposite sides of an electric circuit and the absorbent body 31 is saturated or moistened with water or other suitable liquid, the closing of the electric circuit will establish a current through the liquid or moisture in the element and heat the same so as to generate steam or hot vapor.

As shown, the heating elements 30 are mounted in the casing 15 with an extension of the rivet at one end of each element secured to a conducting bar 40 and an extension of the other rivet of each element secured to a separate conducting post 41. The conducting bar 40 is fixed at one end, as by threaded studs 42 and 43, and nuts to a transverse partition or wall 44 of the casing 15, and one of these studs forms a binding post for connecting the bar with a wire or electrical conductor. Each post 41 is secured to the adjacent side wall of the casing, as by a threaded stud 45 projecting from the post through a hole in the wall and secured therein by a nut, and this stud forms a binding post for the connection of a wire or electrical conductor. Preferably, the rivet extensions of each element are seated in open grooves 46 in the conducting bar 40, and in the companion post 41, and are removably secured therein by screws 47 which enter threaded holes in the bar 40 and post 41, with their heads arranged to overlap and retain the rivet extensions in the seats 46. Thus, each element is removably secured in place and can be quickly and easily removed and replaced by a new element when necessary.

A separate control switch 50 is shown for each heating element so that current may be passed through one, two or all of the elements, as may be desired, by the operation of the appropriate switch or switches, and in addition, the several elements and their control switches are connected in circuit with a conventional time switch 51 adapted to be set for opening the circuit after the element or elements has or have been in ac-

tion for the predetermined desired period of time, depending upon the setting of the time switch. As shown for this purpose, see Fig. 4, the conductor bar 49 is connected by a wire or conductor 52 to one side 53 of the current supply line, with the time control switch 51 interposed between the conductor 52 and the line 53, and the binding post 41 for each element is connected by a wire or conductor 54 at the opposite side 55 of the line with one of the control switches 50 interposed between each conductor 54 and the line 55. Thus, one, two or all of the heating elements can be placed in action, as may be required, and shut off at the end of the desired period of time, by closing one, two or all of the individual control switches 50 and properly setting the time switch. A pilot lamp 56 is shown, suitably connected across the heating circuit so as to be lighted and show when the current is on.

Pieces or bodies 57 of absorbent material, for instance, pieces of sponge, are arranged in the bottom of the treating chamber, also between the inclined end 18 of the casing and the adjacent heating element and also in other spaces between and around the elements. These absorbent bodies are adapted to be saturated or moistened with the liquid to be evaporated by the heating elements, and they act to absorb or take up any free liquid or condensate and prevent the same from collecting as free liquid in the treating chamber. In this way, the possibility of the liquid escaping from the chamber and getting on the person whose hair is being treated, which might otherwise happen if the casing is moved to a downwardly inclined position toward the person, is prevented. If the casing is made of metal or electrically conductive material, the casing body, which forms a receptacle or tank, is preferably made with a lining 60 of rubber or other suitable insulating material, and the fastenings for the electrical conductors for the heating elements may be properly insulated, as usual, from the metal portions of the casing. Also, the electrical conductors may be covered and protected by suitable conduits or housings, as indicated at 61, Fig. 11.

Hair stretching rolls having resilient or yielding peripheries of rubber or analogous material are arranged transversely in the casing or treating chamber. Preferably, these rolls are disposed in a succession of pairs of upper rolls 62 and lower rolls 63, with each pair of rolls spaced somewhat from the next adjacent pair lengthwise of the casing. The lower rolls are journalled to rotate on the body of the casing while the upper rolls are journalled on the cover, so that the rolls of the several pairs are separated by raising the casing cover, thereby permitting a tress of hair to be laid out on the lower rolls so that when the cover is closed, the hair will be between the upper and lower rolls and can be stretched by rotating the rolls. In order to enable the rolls to be readily removed for cleaning them and for cleaning the interior of the casing or giving access to the heating elements or other parts therein, the projecting journals or shaft ends 64 at one end of the lower rolls may be removably seated in bearing holes 65 in a bearing bar 66 suitably secured lengthwise in the casing body adjacent one side thereof, while the journals at the other end of the lower rolls are removably retained in open bearing seats 67 in the top of a longitudinal bearing bar 68 by a retaining bar 69 which extends across and engages the several journals and is removably secured on the bearing bar 66, as by

headed screws 70 passing through keyhole slots in the retaining bar. The bearing bar 68 is preferably removably secured in a channel extending lengthwise in the rear side of the casing body. 5 By removing the retaining bar, which can be quickly done, all of the rolls are released and can be lifted out of their bearing seats. The upper rolls may be journaled in bearing bars 72 and 73 suitably secured in the casing cover at the opposite sides, and may be removably retained in their bearings in the same manner as the lower rolls, by means including a removable retaining bar 74. The bearing bar 73 also is preferably secured removably in a channel in the cover.

15 The rolls of each pair are rotated in opposite directions so that they tend to grip or frictionally engage and propel the hair between them, and thus subject it to a tensioning or stretching action, preferably by the following drive mechanism:

20 A worm shaft 80 arranged lengthwise of the casing to turn in a longitudinal bearing groove in the bearing bar 68 and extending through a bearing in one end of the casing, is adapted to mesh with worm pinions 81, one on the adjacent journal of each lower roll, so as to turn all of the lower rolls in the same direction by rotation of said worm shaft. The several upper rolls are similarly rotated by a worm shaft 82 which is similarly journalled in the bearing bar 73 for the adjacent journals of the upper rolls and meshes with worm pinions 83 on the roll journals. The lower worm shaft 80 is geared at one end, as by bevel pinions 80a, to a cross shaft 84, which is 25 suitably journalled in bearings on the rear end of the casing body and is geared, as by bevel pinions 85 to a crank shaft 86 provided with a crank handle for turning it. This crank shaft 86 extends parallel with the worm shafts at the side of the casing opposite to that at which the cover is hinged, in a position so that when the casing cover is closed, the upper worm shaft 82 is placed adjacent to and is adapted to be geared to the crank shaft 86 by gear wheels 88 and 89 connected to the worm and crank shafts. As shown, the crank handle has a hub or sleeve 90 which is movable lengthwise on but splined to the shaft 86 to turn therewith, and the gear wheel 89 is 30 fixed on the sleeve 90. The crank sleeve 90 is normally urged outwardly, as by a coil spring 91 surrounding the crank shaft between the bevel pinion 85 and the gear 89 to hold the gear out of the plane of the gear 88 on the upper worm shaft, as shown in Fig. 13. Thus, when closing the 35 cover, the gear 88 on the upper worm shaft will not strike or mesh with the gear 89, but the gear 88 can be moved axially into mesh with the gear 89 by pressing the crank handle inwardly, when by turning the crank, both worm shafts will be turned and will drive all of the rolls. This arrangement of the drive mechanism prevents possible striking and mutilation of the gearing in closing the casing cover. Gear housings 92, 93 are preferably provided on the casing body and 40 cover for enclosing the cross shaft 84 and the gearing connecting it with the worm shafts and crank shaft.

45 94 represents a vent for steam from the treating chamber 16, preferably formed by a pipe 70 leading from the upper front portion of the chamber to a hole passing through the top wall of the casing cover 17 into a receptacle or trap 95, which may be formed by a piece of tube secured in a socket on the cover. Steam can escape 50 from this vent and serve to indicate when the 55

desired steam condition for hair treatment exists in the treating chamber and also to prevent the steam pressure in the chamber from becoming too high. Any condensation of steam at the outer end of the vent pipe will be prevented, by the receptacle 95, from escaping onto the outside of the casing. The receptacle also serves as a funnel or enlarged opening for pouring liquid into the treating chamber during a treatment of hair, if this is necessary or desired, without requiring the casing cover to be opened.

As before stated, the casing 15 is adjustably mounted so that it can be adjusted to different positions, as may be necessary to most conveniently treat tresses or portions of the hair on different portions of the subject's head. For this purpose, the casing is mounted on a stand or support which, in the construction illustrated in the drawings, comprises a base 96 adapted to rest on the floor, and a standard or post 97 which supports the casing and is adapted to be adjusted to and held in different vertical adjustments in the upright column of the base by a crank-operated worm gearing 98 and a pinion meshing with a rack 99 on the standard. The standard preferably has a laterally inclined arm on which a swivel head 100 is mounted so that it can be turned horizontally about a vertical axis by suitable worm adjusting gearing 101. The casing 15 is mounted on the head 100 through the medium of a bracket 102 which is pivoted to the head to swing about a horizontal axis 103 extending lengthwise of the casing, while the casing is pivoted to the bracket 102 to swing about a horizontal axis 104 which is perpendicular to the axis 103. Therefore, the casing is adapted to swing or tilt in a vertical plane extending lengthwise of the casing about the axis 104 and also to swing or tilt in a vertical plane transverse to the casing about the axis 103. A worm and worm-sector gearing 105 is provided for effecting one of these adjustments, and a second worm and worm-sector gearing 106 is provided for effecting the second adjustment. Thus, the casing is adapted to be easily adjusted universally or horizontally and in vertical planes at right angles to each other and held stationary in any of these adjustments, whereby the casing can be swung around horizontally and its front end tipped up or down, and also given an oblique or transversely inclined position in any one of its other adjustments, as may be necessary.

The mechanisms for effecting these adjustments are not disclosed and described in further detail as they form the subject matter of another application and are not claimed herein, but it will be understood that the casing is not merely adjustable to these different positions, but is provided with mechanism for adjusting it to and holding it steady or stationary in any desired universal adjustment.

By employing the described heating elements 30, the apparatus can be used for treating hair with entire safety. The heating elements will heat up only when their absorbent bodies 31 are moist or liquid is present. Consequently, no damage can be done in their use either to the hair or the elements themselves, since if they become dry, they will not function and, so long as they are moist, they will generate steam or moist heat which prevents injury to the hair or elements.

The apparatus constructed as shown and described, in addition to its use for straightening hair, is also adapted for efficiently treating the 75

hair to obtain other desired results. Hair can be revivified or a deficiency in oil therein rectified by subjecting the hair to the steam heat in the heating chamber and operating the rolls to put

5 a gentle tension on the hair, a suitable oil or ointment having first been applied to the hair. By this treatment, the scales of the hair are loosened or opened up so that the oil or ointment, which is rendered more fluid by the heat, 10 more readily and efficiently penetrates the hair.

Also, curly hair can be revivified or enlivened by similarly treating it with a suitable oil or ointment and subjecting it to the steam heat in the apparatus, but without stretching or subjecting 15 the hair to tension by means of the rolls so as not to remove the curl. When performing this treatment, if desired the upper rolls can be removed and the hair permitted to lie in its curly state in the treating chamber upon the lower rolls. The 20 apparatus is also desirable for removing dye from hair. When so used, a suitable solvent for the dye is applied to the hair and the hair then subjected to the steam treatment in the treating chamber with or without subjecting the hair to the action of the rolls, depending upon whether 25 or not it is desired to also straighten the hair. The steam treatment materially facilitates and expedites the action of the solvent in removing the dye. Other treatments of hair, in which it 30 may be desired for any reason to subject the hair to the action of steam or a hot, moist atmosphere, can be performed by the apparatus.

We claim:

1. A device for treating hair comprising a sectional casing providing a treating chamber, and 35 adapted to be opened for placing therein for treatment a tress of the hair of a person's head, means for stationarily supporting said casing in different adjusted positions with one end thereof 40 close to the head, means for clamping and holding the tress adjacent to the head, means in said casing for holding a liquid, means for heating the liquid in the casing to generate steam in said chamber, and means constructed and arranged to subject the hair in the chamber to a straightening tension in the presence of the 45 steam.

2. A device for treating hair as set forth in 50 claim 1, in which the hair tensioning means comprise rolls in the casing between which the tress passes and is gripped, and means for rotating said rolls to stretch the hair while it is being treated by the steam.

3. A device for treating hair comprising a sectional casing providing a treating chamber and 55 adapted to be opened for placing therein for treatment a tress of the hair of a person's head, means for stationarily supporting said casing in different adjusted positions with one end thereof 60 adjacent the head, absorbent material in the lower portion of said chamber adapted to hold a liquid, a heating element incorporated in said device for heating the liquid in said absorbent material, to generate steam in said chamber, and means for supporting the tress of hair extended lengthwise in the chamber over said absorbent material.

4. A device for treating hair as set forth in 65 claim 3 in which said heating means comprises an electrical heating element for said liquid.

5. A device for treating hair, as set forth in claim 3, and provided with a steam vent for said chamber which opens into the chamber at the end thereof which is adjacent to the head.

6. A device for treating hair, as set forth in

claim 3, and provided with a trap for condensed vapor on top of said casing, and a steam vent pipe communicating with said trap and with said chamber at the end thereof adjacent the head.

7. A device for treating hair, as set forth in claim 3, and provided with a steam vent tube communicating with said chamber at the end adjacent the head and opening out of the top of the casing at a point remote from the head.

8. A device for treating the hair of a person's head comprising a casing providing a treating chamber and having sections hinged together to open book-fashion for placing a tress of hair therein for treatment, treating means for the hair in the chamber, and means for supporting said casing with one end thereof adjacent the person's head, the hinge means for said casing sections being constructed and arranged to adapt one section to swing toward and from the other section and also to move lengthwise relatively to the other section while the sections occupy relatively adjacent opposed positions.

9. A device for treating hair, as set forth in claim 8, in which said hinge means enables movement of one section longitudinally relative to the other and allows swinging movements of said section of a limited extent only in one longitudinal position of said section and of a greater extent in a different longitudinal position of the section.

10. In a device for treating hair comprising a casing having hinged sections providing a treating chamber and adapted to be opened for placing a tress of hair therein for treatment by an agent in the chamber and adapted to be supported with one end thereof adjacent the subject's head, and means for subjecting the hair in the chamber to a stretching action while being treated, comprising elements carried by said casing sections and between which the hair passes, the improved hinge means for said casing sections which is constructed and arranged to enable movement of one section relatively to the other toward and from the head and allow an extended swinging movement of the section when moved to a position away from the head, but limit the swinging movement to a lesser extent when the section is in a position adjacent the head.

11. In a device for treating hair comprising a sectional casing providing a treating chamber and adapted to be opened for placing a tress of hair therein for treatment, rolls arranged in successive pairs in said chamber and between which the hair is gripped, and means for oppositely rotating the rolls of said pairs to subject the hair to a stretching action, an electrical heating element in said chamber comprising electrodes and an absorbent body adapted to hold moisture between said electrodes, and means for including said element in an electric circuit for heating said liquid to generate steam in said chamber.

12. In a device for treating hair comprising a sectional casing providing a treating chamber and adapted to be opened for placing a tress of hair therein for treatment, and stretching means arranged in said chamber and comprising elements arranged to be separated for receiving the hair between them by opening the casing, and means for actuating said stretching means to subject the hair to a stretching action, an electrical heating element in said chamber comprising electrodes and an absorbent body adapted to hold moisture between said electrodes, and means for including said element in an electric circuit

for heating said liquid to generate steam in said chamber for treating the hair while being stretched.

13. In a device for treating hair comprising a sectional casing providing a treating chamber and adapted to be opened for placing a tress of hair therein for treatment, rolls arranged in successive pairs in said chamber and between which the hair is gripped, and means for oppositely rotating the rolls of said pairs to subject the hair to a stretching action, an electrical heating element in said chamber below said rolls, comprising electrodes and an absorbent body adapted to hold liquid between said electrodes, means for including said element in an electric circuit for heating said liquid to generate steam in said chamber for treating the hair while being stretched, and an absorbent body adapted to contain liquid in the lower portion of said chamber and adapted to be heated by said element.

14. In a device for treating hair comprising a sectional casing providing a treating chamber and adapted to be opened for placing a tress of hair therein for treatment, rolls arranged in said chamber and between which the hair is gripped, and means for oppositely rotating said rolls to subject the hair to a stretching action, a plurality of electrical heating elements in said chamber each comprising electrodes and an absorbent body adapted to hold moisture between said electrodes, whereby steam is generated by the passage of electric current through said elements, control means for including one or more of said heating elements in an electric circuit, and a time switch for shutting off the current after a predetermined period of time.

15. In a device for treating hair comprising a sectional casing providing a treating chamber and adapted to be opened for placing a tress of hair therein for treatment, rolls arranged in said chamber and between which the hair is gripped, and means for oppositely rotating said rolls to subject the hair to a stretching action, a plurality of electrical heating elements in said chamber, below said rolls and each comprising electrodes and an absorbent body adapted to hold moisture between said electrodes, whereby steam is generated by the passage of electric current through said elements, control means for including one or more of said heating elements in an electric circuit, a time switch for shutting off the current after a predetermined period of time, and absorbent bodies adapted to contain a liquid and arranged in the lower portion of the chamber between said heating elements and between the heating elements and one end of the chamber.

16. A device for treating hair, comprising a casing having sections and adapted to be opened and closed by movement of one section, hair treating rolls arranged in opposed sets one mounted on each casing section, two shafts one carried by each casing section and geared to the rolls on that section, a rotatable driving device for said shafts which is operatively connected with one of said shafts, and gear wheels connected to said driving device and to said second shaft and arranged to be placed adjacent but out of mesh with each other by closing said movable casing section, axial movement of said driving device placing said gear wheels in mesh for operatively connecting the driving device also with said second shaft.

17. A device for treating hair, comprising a casing composed of sections hinged together at

one side of the casing and adapted to be opened and closed by movement of one section, hair treating rolls arranged in opposed sets one mounted on each casing section, two shafts one carried by each casing section and geared to the rolls on that section, a rotatable driving device for said shafts which is operatively connected with one of said shafts, said shafts being located one at the hinge side of one casing section and the other at the opposite side of the other casing section, a rotatable driving device for said shafts which is geared to said shaft at the hinge side of the casing but is located adjacent the opposite side of the casing, and gear wheels carried by said driving device and by said second shaft and arranged to be placed adjacent but out of mesh with each other by closing said movable casing section, axial movement of said driving device placing said gear wheels in mesh for gearing the driving device also to said second shaft.

18. In a device for treating hair comprising a rigid walled casing providing a treating chamber in which the hair is adapted to be enclosed, rolls in the casing between which the hair is gripped, and means for oppositely rotating the rolls to stretch the hair, an absorbent body in said casing adapted to hold liquid, and electrical means incorporated in said device for heating said liquid to generate steam in said chamber for conditioning the hair while it is being stretched by said rolls.

19. In a device for treating hair comprising a sectional casing providing a treating chamber and adapted to be opened for placing a tress of hair therein for treatment, rolls arranged in successive pairs in said chamber and between which the hair is gripped, and means for oppositely rotating the rolls of said hairs to subject the hair to a stretching action; an absorbent body in the chamber adapted to hold liquid, and an electrical heating element in said casing, and means for including said element in an electric circuit for heating said liquid to generate steam for treating the hair while being stretched.

20. In a device for treating hair comprising a sectional casing providing a treating chamber and adapted to be opened for placing a tress of hair therein for treatment, stretching means arranged in said chamber and comprising elements arranged to be separated for receiving the hair between them by opening the casing, and means for actuating said stretching means to subject the hair to a stretching action; an absorbent body in the chamber below said stretching means and adapted to hold liquid, and an electrical heating element and means for including said element in an electric circuit for heating said liquid to generate steam for treating the hair while being stretched.

21. In a device for treating hair comprising a sectional casing providing a treating chamber and adapted to be opened for placing a tress of hair therein for treatment, rolls arranged in successive pairs in said chamber and between which the hair is gripped, and means for oppositely rotating the rolls of said pairs to subject the hair to a stretching action; an absorbent body adapted to hold liquid, and an electrical heating element in said chamber beneath said rolls, means for including said element in an electric circuit for heating said liquid to generate steam for treating the hair while being stretched, and an absorbent body adapted to contain liquid in the lower portion of said chamber and adapted to be heated by said element.

22. In a device for treating hair comprising a sectional casing providing a treating chamber and adapted to be opened for placing a tress of hair therein for treatment, rolls arranged in said chamber and between which the hair is gripped, and means for oppositely rotating said rolls to subject the hair to a stretching action; a plurality of electrical heating elements in said chamber, means adapted to hold liquid in the chamber to be heated by said heating elements, whereby steam is generated in the chamber for heating the hair while being stretched, by the passage of electric current through the elements, control means for including one or more of said heating elements in an electric circuit, and a time switch for shutting off the current after a predetermined period of time.

23. In a device for treating hair comprising a sectional casing providing a treating chamber and constructed to be opened for placing a tress of hair therein for treatment, rolls arranged in said chamber and between which the hair is gripped, and means for oppositely rotating said rolls to subject the hair to a stretching action; holding means for a liquid in said chamber, a plurality of electrical heating elements in said chamber whereby said liquid is adapted to be heated and steam generated in the chamber by the passage of electric current through said elements, control means for including one or more of said heating elements in an electric circuit, a time switch for shutting off the current after a predetermined period of time, and absorbent bodies adapted to contain liquid and arranged in the lower portion of the chamber between said heating elements and between the heating elements and one end of said chamber.

24. In a device for straightening curly hair, comprising a casing providing a treating chamber in which a tress of hair is adapted to be enclosed, and means constructed and arranged to effect a straightening tension on the hair in said chamber, means adapted to hold a liquid in said chamber, and a heater incorporated in the device for heating said liquid in the chamber to generate vapor for conditioning the hair while it is being subjected to said straightening tension.

25. A device for treating hair on a person's head comprising a rigid walled casing providing a treating chamber in which the hair is adapted to be enclosed, means for stationarily supporting said casing in different adjusted positions relative to the person's head, means adapted to hold a liquid in said casing, a heating element for heating said liquid in the casing to generate vapor in the chamber, and means constructed and arranged to subject the hair in the chamber to a straightening tension in the presence of said vapor.

26. In a device for treating hair comprising a rigid walled casing providing a treating chamber in which the hair is adapted to be enclosed, rolls in the casing between which the hair is gripped, and means for oppositely rotating the rolls to effect a straightening tension on the hair, an absorbent body in said casing adapted to hold liquid, and means for including said liquid in an electric circuit for heating the liquid to generate steam in said chamber for conditioning the hair while it is being subjected to said straightening tension.
